STONE SPREADER

Application filed August 13, 1927. Serial No. 212,764.

This invention relates to improvements in stone spreaders, and more particularly to an attachment for trucks to be used in the spreading of crushed stone, gravel and like materials on roads in the course of construction or in the resurfacing or repairing thereof.

The object of the invention is to provide a spreading device to be mounted at the rear of a truck for the purpose of spreading crushed stone or like road building materials over the roadway in a layer of uniform thickness as the truck is being propelled forwardly over the area to be covered.

15 A further object of the invention is to facilitate the construction and repair of roads by eliminating labor cost of handling road building materials by making it possible to spread the same from a moving vehicle without the intermediate steps usually employed, namely, of dumping the materials along the road and then spreading it by hand.

20 A preferred embodiment of the invention is disclosed in the accompanying drawings, in which

Figure 1 is a top plan view of the attachment showing its position on a truck body,

25 Figure 2 is a view of the spreading attachment in rear elevation, that is, from behind the truck,

Figure 3 is a view in front elevation of the spreader as taken on section line 3—3 of Figure 1,

30 Figure 4 is a view in end elevation of the spreader, and

Figure 5 is a view in vertical section through the spreader as taken on line 4—4 of Figure 3, with the truck body tilted into dumping or spreading position as shown in dotted lines.

As suggested from the foregoing discussion, the spreading device is essentially an attachment to be mounted upon the rear end of a truck body A, preferably of the self-dumping type in which the front end is elevated to discharge the contents by gravity from the rear end.

The spreading device comprises in general, a box-like receptacle of sheet metal, so mounted on to the truck body as to project

beyond the rear and sides thereof and having an adjustable opening extending the width thereof through which the material is discharged.

The spreader is constructed of sheet metal, shaped to form the walls, and reinforced by structural steel members where required.

Considering the front of the spreader as that portion adjacent the truck, it will be observed that it encloses the rear portion of the truck body, so that it has in reality no front walls except two wall portions or wings 1, 1 extending laterally from the side walls of the truck body, the length of the spreader being somewhat greater than the width of the body and projects beyond the same at both ends. End walls 2, 2 extend rearwardly from the front wall portions 1, 1 and unite with rear and bottom walls 3 and 4, all of the same being preferably formed from a single piece of sheet metal and bent into shape.

The top edges of the side walls 2, 2 slope downwardly toward the rear, so that the spreader is rather more shallow at its rear portion than at its forward portion. The top of the spreader is open, except at the ends where top wall sections 5, 5 are carried inwardly from the end walls and thence tapering off in points 5a, 5a along the top edge of the rear wall 3, the latter preferably having a rectangular section removed between the inner ends of the top wall sections to form a central portion 3a of reduced height. The rear wall is strengthened by an angle bar 6 extending horizontally above the lower edge and riveted to the outer face thereof, its ends being bent around the corners and riveted to the end walls. The bottom wall 4 consists of a fixed front section 4a extending from the front edge of the device to a point substantially midway of its width, and a hinged section 4b consisting of a plate joined to the fixed portion by four strap hinges 7 riveted to the under side of the bottom wall sections.

Along the outer edge of the hinged plate 4b is an angle bar 8, with one web riveted flatwise against the bottom of the plate and the other projecting downwardly in line with the edge thereof. The ends of the angle bar 100

8 extend a short distance beyond the ends of the plate and are provided with bosses in the horizontal web portions thereof. These bosses being tapped to receive a pair of adjusting bolts 9, 9 extending upwardly and hung in brackets 10, 10 riveted to the end walls 2, 2. These brackets have laterally projecting wings or flanges 10a, 10a with elongated slots 10b, 10b formed therein and through which the bolts 9, 9 extend, the heads of said bolts bearing against the webs 10, 10a.

It is manifest that by adjusting the bolts 9, 9 the hinged bottom wall section or plate 15 4b can be raised or lowered, thus providing a slot or discharge opening of desired width between the outer edge of the plate and the bottom edge of the rear wall 3.

As a preferable means of attaching the spreader to the truck body, the following means are used: For the purpose of illustration it is assumed that the truck body A of the elevating dump type as already suggested, consists of an open box of steel construction, having a swinging gate B at its rear end hinged at b, b to swing outwardly along its upper edge. It may also be assumed that the structure of the body also includes a pair of angle bars C, C spaced a short distance forwardly of the rear end thereof and extending vertically on each side of the body, and a third bar D extending crosswise underneath the body between the lower ends of the bars C, C. As so located these bars provide a continuous flange extending at right angles from the three sides of the body. It is to these flanges that the spreader is bolted. In the first place, the inner vertical edge of the front wall portions or wings 1, 1 of the spreader abut against the flanges of the upright body angle members C, C. Bolt holes are drilled through the vertical inner edges of the wall portions 1, 1, and bolts 1a inserted through these holes and registering holes in the flanges of the body bars C, C. For securing the spreader underneath the truck body an angle bar 11 is riveted along the front edge of the bottom wall 4 so as to provide an upwardly projecting web or flange in which are drilled a plurality of bolt holes. In applying the spreader the vertical flange of the angle iron 11 abuts against a corresponding flange of the under body bar D and bolts 11a are inserted through holes in these flanges.

The manner in which the spreader operates is obvious: Having been attached to the rear of a vehicle, the opening along its bottom rear edge is adjusted to the proper width, depending upon the grade of material used and the thickness of the layer to be spread. The truck with its load of material is then driven to the point where the spreading is to begin, and the body elevated or tilted so that the action of gravity causes the material to

flow into the spreader as soon as the gate B of the body is released, the weight of the material forcing the gate open and to stand in open position while the material flows into the spreader and thence in a stream of uniform thickness from the discharge slot of the spreader. The volume discharged from the spreader will manifestly be governed by the speed of travel of the truck as well as on the angle to which the body is tilted into dumping position. Ordinarily a relatively slow constant speed is maintained during the discharging of each load of material on the roadway, and the elevation or tilt of the body increased as the load diminishes. Thus at the start with a full load the body need only be tilted sufficiently to fill the spreader, but as the rear end of the truck becomes empty the body is tilted more and more so that the material at the front end of the truck will be carried toward the rear until the entire load is discharged.

By the use of the spreading attachment it is obvious that all unnecessary handling of the material is eliminated, since the unloading and spreading operations are combined in a single operation in which gravity and motive power replace the slow and tedious manual labor of spreading the material by hand shovels.

Having disclosed a preferred embodiment of the invention, we claim:

1. A spreader attachment for a vehicle dump body comprising an elongated box-like receptacle mounted at the rear of said body and having covered end portions extending beyond the sides thereof, the front wall of said receptacle being reduced in height intermediate its ends to provide a recess embracing the rear end of said vehicle body, and a movable wall section extending longitudinally of said receptacle below the level of the body, and means for adjusting said wall section to form a discharge slot adjacent the bottom rear edge of said receptacle.

2. A spreader attachment for a vehicle dump body comprising a receptacle extending transversely of the rear end of said body and having front, rear and bottom walls, said front wall being reduced in height intermediate its ends to provide a recess embracing the rear end of said vehicle, top wall sections covering the end portions of said receptacle, a hinged wall section at the lower rear end of said receptacle, and means for adjusting the same to form a discharge slot of different widths.

Signed at Avalon, Calif., this 6th day of August, 1927.

DAVID M. RENTON.
